WIDE DYNAMIC RANGE SQUARE-LAW DETEC-
TOR WITH LOGARITHMIC READ-OUT
Ralph H. Britton, Jr., Palo Alto, Calif., assignor to
Alfred Electronics, Palo Alto, Calif., a corporation
of California
Filed June 16, 1966, Ser. No. 558,091
10 Claims. (Cl. 329—192)

This invention relates to detection systems for recovering the signal modulated upon a carrier, and more particularly, to a crystal diode detector system which provides logarithmic read-out over the entire detection range of the crystal diode.

Most high frequency detection systems are non-linear and have a transfer characteristic which is the function of the applied RF power. A crystal detector, for example, has a square-law characteristic for small signals and a linear characteristic for large signals. The transition area between small and large signals has a characteristic which changes, as the applied signal power is increased, from square-law to linear.

This non-linearity of the crystal detector characteristic has given rise to a number of problems when it is desired to employ the full detection range of the crystal diode. The term full detection range, as herein used, refers to the application of signals whose RF power ranges from being substantially equal to zero to being substantially equal to the crystal reverse breakdown voltage. Accordingly, the full detection range covers the square-law region, the transition region and the linear region.

One problem attributable to the non-linear characteristic of the crystal detector is the imposition of certain limitations upon the user who requires significant values of the detected signal. For example, many users of crystal detectors limit the range of the input signal to small signals, typically below 50 millivolts, so that the detected output signal conforms to the typical square-law characteristic. Other users who are primarily interested in larger signals limit the detection to large signals, typically above 1 volt, so that the detected output signal conforms to the typical linear characteristic. The intermediate regions, where the crystal exhibited a transition characteristic between square-law and linear, is generally avoided when the user required significant values of the detected signal.

In those instances, where a user required significant values of the detected signal throughout the small signal range and beyond, complex compensating circuitry has been employed to convert the detected signals lying in the transition region into square-law values. However, such compensating circuitry has not been found entirely satisfactory, particularly when the power of the applied RF signal tended to approach the large signal range. Further, the cost of such compensating circuitry is high and its reliability, due to its complexity, left something to be desired.

It is therefore a primary object of this invention to provide a detection system capable of providing significant values of the detected signal over the entire detection range of a crystal detector.

It is a further object of this invention to provide a square-law detection system which has a logarithmic read-out over a dynamic range which is wider than was possible heretofore.

It is still another object of this invention to provide a detection system which has an effective square-law characteristic, as seen at the output, over the entire detection range of a crystal detector, that is, a range extending from small signals up to the reverse crystal diode breakdown voltage.

It is still another object of this invention to provide a

2

detection system which has a logarithmic read-out which is linear with respect to the RF signal input power and whose range extends from typical small signals up to the reverse breakdown voltage of the crystal diode.

5 Further objects and advantages of the present invention will become apparent to those skilled in the art to which the invention pertains as the ensuing description proceeds.

The features of novelty that are considered characteristic of this invention are set forth with particularity in 10 the appended claims. The organization and method of operation of the invention itself will best be understood from the following description when read in connection with the accompanying drawings in which:

FIGURE 1 is a schematic block diagram of the wide dynamic square-law detector with logarithmic read-out of this invention;

FIGURE 2 is a schematic diagram, partially in block form and partially in circuit form, of one embodiment of the step gain amplifier illustrated in FIGURE 1;

20 FIGURE 3 is a typical graph of the detected voltage versus RF voltage characteristic of a crystal detector and is useful in explaining the operation of this invention;

FIGURE 4 is a graph of the logarithm of the detected voltage versus RF voltage characteristic of the graph shown in FIGURE 3;

FIGURE 5 is a graph of the amplification versus RF voltage characteristic of the stepped gain amplifier of FIGURE 2; and

30 FIGURE 6 is a graph of the logarithm of the detected voltage versus RF voltage of the detector system of this invention.

Referring now to FIGURE 1 of the drawing, the detection system thereshown comprises a detector means 10 having an input terminal 11 to which the RF signal to be detected is applied, a logarithmic gain amplifier means 13 connected to the output terminal of detector means 10 via a lead 12 and a stepped gain amplifier means 15 connected to the output terminal of logarithmic gain amplifier means 13 through a lead 14. The output lead of stepped gain amplifier means 15 is connected to a system output terminal 16.

Detector means 10 may take the form of any of the wellknown crystal diodes which has a resistance to current flowing in one direction which is very much greater than to current flowing the opposite direction and thereby produces the rectifying action. In response to an RF input signal, applied to terminal 11, detector means 10 will detect the signal and provide the detected signal on output lead 12.

55 Logarithmic gain amplifier means 13 is an amplifier whose gain varies as the logarithm of the applied input voltage and which thereby provides an output signal which is the logarithm of the input signal. Amplifier means 13 may take the form of a feedback amplifier system having a high gain operational amplifier in its forward loop and a transistor in its feedback loop. The transistor acts as a three-terminal feedback network by having its collector and emitter respectively connected to opposite sides of the operational amplifier and its base is grounded. If the 60 transistor selected is a silicon transistor, it exhibits a short circuit collector current which is proportional to the exponential of the emitter-base voltage over 9 decades of collector current and which thereby provides an amplifier whose output signal is the logarithm of the input signal. Logarithmic gain amplifiers of this type are well-known to those skilled in the art and are fully described in a number of publications, including an article by J. F. Gibbons and H. S. Horn entitled "A Circuit With Logarithmic Transfer Response Over 9 Decades," IEE Transactions of the Professional Technical Group on Circuit Theory, Sept. 1964, pp. 378-384.

Stepped gain amplifier means 15 is an amplifier whose amplification increases step-wise with increase in the amplitude of the applied signal on lead 14 from an amplification of "A" to an amplification of "2A." Referring now to FIGURE 2, there is shown one embodiment of stepped gain variable gain amplifier means 15. Amplifier means 15, as thereshown, comprises a differential, high-gain amplifier 20 having one of its input terminals connected to lead 14 to receive the output signal from logarithmic amplifier means 13. There is also provided a feedback network, generally designated by reference character 21, between the output lead of amplifier 20 and the other of its input terminal. Feedback network 21 includes a voltage divider, formed by resistors 22 and 23, which determines the amount of feedback signal which is fed back to amplifier 20 and, thereby, the amplification of stepped gain amplifier means 15 for small signals applied to input lead 14. This amplification will be arbitrarily designated as "A."

Feedback circuit 21 is also provided with means for step-wise increasing the feedback signal with preselected increases in the amplitude of the amplifier output signal and thereby the feedback signal and amplification. More particularly, a plurality of resistive branch arms are connected in parallel to feedback circuit 21 through individual switches. FIGURE 2 illustrates four branch arms connected to feedback circuit 21 through diodes 24, 25, 26 and 27 which are back biased to operate as voltage switches. The diodes are connected respectively, through resistors 28, 29, 30 and 31 to a voltage divider network formed by the series connected resistors 32, 33, 34, 35 and 36. This voltage divider has a pair of terminals 37 and 38 which are respectively connected to the negative and positive output terminal of a source of reference voltage for back biasing the diodes.

Resistors 28 to 36 are selected in such a manner that switch diodes 24 to 27 are normally back biased when the voltage across resistor 22 is small and become forward biased when the voltage across resistor 22 is large. Further, the resistive values of the various resistors are selected so that when the feedback voltage is large, the amplification of stepped gain amplifier means becomes "24" or twice the amplification for the small feedback voltage. Still further, the resistive values of the various resistors is selected so that the first step-wise increase of amplification occurs when the signal applied to amplifier means 15 has an amplitude corresponding to a detected signal at the very beginning of the transition region of the crystal diode, and that the last step-wise increase occurs when the signal applied to amplifier means 15 has an amplitude corresponding to a detected signal at the very end of the transition region. The intermediate step-wise increases in the amplification are selected to provide a smooth transition as will become better understood in connection with the description of the operation of this invention.

The operation of the detector system of this invention is best understood by reference to FIGURES 3-6. FIGURE 3 depicts a curve 50 which is the typical detected voltage versus RF voltage (voltage-current) characteristic of a crystal detector, such as, for example, detector means 10. Curve 50 is typical in that it shows that for small signals the rectified output voltage increases rapidly with increase of RF voltage as shown by portion 51, then less rapidly for intermediate signals as shown by portion 52, and then even less rapidly for large signals as shown by portion 53. Portion 51 shows the rectified output voltage as proportional to the square of the RF input voltage, portion 53 shows the rectified output voltage as directly proportional to the RF input voltage, and portion 52 is the transition region through which the rectified output voltage changes from being proportional to the square of the RF input voltage to being proportional directly to the RF input voltage. Portion 51 is known as the square-

law region, portion 52 is known as the transition region, and portion 53 is known as the linear region.

While crystal rectifiers differ in their characteristic with the type of crystal used, and to a smaller extent from crystal to crystal, the square-law region usually ranges from a rectified output voltage between zero and 50 millivolts, the transition region extends usually from a rectified output voltage between 50 millivolts and 1 volt and the linear region extends from a rectified output voltage of 1 volt to the remainder of the useful range of the crystal rectifier as determined by the reverse breakdown voltage and/or the burn-out current which is typically 3 volts, but may be as high as 6 volts for certain crystals.

Accordingly, if rectified output voltage is y and the RF voltage is x , the following equations describe the crystal diode:

$$y = K_1 x^2 \text{ when } 0 < x < X_1$$

$$y = f(x) \text{ when } X_1 < x < X_2$$

$$y = K_2 x \text{ when } X_2 < x$$

where X_1 is the square-law region limit and X_2 is the linear region limit. Taking the logarithms of these equations shows the existence of two linear regions, one below X_1 and the other above X_2 , having a slope differing by a factor of two.

The effect of passing the rectified voltage through logarithmic gain amplifier means 13 is shown by curve 60 of FIGURE 4 which is also the graphical presentation of the equations. The logarithm of the rectified output voltage for RF voltages between 0 and A is linear and depicted by portion 61 of curve 60. The logarithm for the rectified output voltage for RF voltage between b and c is also linear as depicted by portion 63 of curve 60 but has a slope which is only one-half of the slope of portion 61. Portion 62 of curve 60 depicts the transition region which is non-linear and along which the slope decreases by a factor of 2 as the RF voltage changes from a to b .

Referring now to FIGURE 5, there is shown a curve 70 which depicts the amplification of stepped gain amplifier means 15 as a function of the applied RF input voltage (suitably scaled). Curve 70 has the number of steps which are designated by reference characters 71 through 75. Amplifier means 15 is constructed so that for a rectified input voltage corresponding to an RF voltage up to a volts the amplification is equal to A as shown by step 71. Furthermore, when applied rectified input voltage corresponds to an RF voltage in excess of b volts, amplifier means 15 provides an amplification equal to $2A$ as shown by step 75. In the transition region between a and b volts of the applied RF voltage, amplifier means 15 provides a number of intermediate steps of amplification as shown by steps 72, 73 and 74 corresponding, respectively, to an RF voltage range in volts extending from a to s , s to t and t to b .

When the signal shown by curve 60 of FIGURE 4 is passed through stepped amplifier means 15 and thereby subjected to the different amplifications as shown by curve 70 of FIGURE 5, an output signal corresponding to curve 80 of FIGURE 6 is obtained which represents a graph of the rectified output voltage of the system of FIGURE 1 versus the applied RF input voltage. More particularly, the signal corresponding to portion 61 of curve 60 is subjected to an amplification A and the signal corresponding to portion 63 of curve 60 is subjected to an amplification of $2A$ whereby its slope is increased by a factor of 2. This is shown by portions 81 and 85 of curve 80. The portions of curve 60 corresponding to rectified signals of RF input voltages between a and s , s and t , and t and b , are amplified in steps as shown by portions 72, 73 and 74 to provide an amplified output signal corresponding to portions 82, 83 and 84 of curve 80. In this manner the transition portion is linearized in steps to form a straight line with portions 81 and 85.

Referring now to the operation of amplifier means 15

shown in FIGURE 2, amplification A is obtained through the proper selection of resistors 22 and 23 with switches 24, 25, 26 and 27 back biased and therefore closed. The back bias applied to switches 24, 25, 26 and 27 by the voltage divider are selected to correspond, respectively, to RF input signals of a , s , t and b volts. Accordingly, as the RF input voltage reaches a value of a volts, switch 24 becomes forward biased to connect resistor 28 into the circuit and to increase the feedback signal and therefore the amplification of amplifier means 15 to correspond to step 72 of curve 70.

Similarly, when the RF applied input voltage reaches values corresponding to s , t and b volts, switches 25, 26 and 27 become forward biased and connected to additional branch arms into feedback circuit 21 to increase, in steps, the feedback voltage and thereby the amplification. Resistors 28 to 36 are selected such that the stepwise increasing amplification corresponds to steps 72, 73, 74 and 75 of curve 70.

Even though amplifier means 15 has been illustrated as having three intermediate steps of amplification between a minimum amplification of A and a maximum amplification of 2A, it is to be understood that the transition between these amplifications can be accomplished with a lesser or greater number of steps, depending on the deviation from linearity which can be tolerated. For very precise applications and particularly where the RF signals to be detected primarily fall into the transition region of the crystal detector, a much larger number of amplification steps may be provided by the addition of additional switching diodes such as 24 to 27 and corresponding branch arms.

There has been described a wide dynamic range square-law detector with logarithmic read-out which provides a linear output signal over the whole usable range of a crystal rectifier. The output signal is the log of the input signal of the signal to be detected and extends over a range from substantially zero to RF input voltage to the reverse breakdown voltage of the crystal detector. This results in an increase of at least 3 decades of the dynamic range over that of conventional crystal detectors.

While the above detailed description has shown, described and pointed out the fundamental novel features of the invention as applied to various embodiments, it will be understood that various omissions and substitutions and changes in the form and details of the device illustrated may be made by those skilled in the art, without departing from the spirit of the invention. It is the intention, therefore, to be limited only as indicated by the scope of the following claims.

What is claimed is:

1. A detector system for recovering a signal modulated upon a carrier, comprising in combination:

crystal detector means to which the modulated carrier is applied and which provides a detected signal, said crystal detector means having a square-law region for small amplitude detected signals, a linear region for large amplitude detected signals and a transition region for intermediate amplitude detected signals; a logarithmic gain amplifier responsive to said detected signal and operative to provide a first signal, said logarithmic gain amplifier having gain which varies as the logarithm of the amplitude of said detected signal; and

variable gain amplifier means responsive to said first signal and operative to provide a second signal, said variable gain amplifier means having a gain which varies with the amplitude of said first signal.

2. A detector system in accordance with claim 1 in which said variable gain amplifier means has a gain which increases stepwise with the amplitude of said first signal from a first gain to a second gain.

3. A detector system in accordance with claim 2 in which said second gain is equal to twice said first gain.

4. A detector system in accordance with claim 3 in which the gain of said variable gain amplifier means equals said first gain for all first signals corresponding to small amplitude detected signals, and said second gain for all first signals corresponding to large amplitude detected signals.

5. A detector system in accordance with claim 2 in which the gain of said variable gain amplifier means is substantially constant for all first signals corresponding to small and large amplitude detected signals, and stepwise increases with the amplitude of said first signal for first signal corresponding to intermediate amplitude detected signals.

6. A detector system in accordance with claim 1 in which the gain variation of said variable gain amplifier with the amplitude of said first signal are selected so that said second signal becomes the logarithm of the signal modulated upon the carrier.

7. A detector system in accordance with claim 5 in which the gain of said variable gain amplifier means for first signals corresponding to large amplitude detected signals is double the gain for first signals corresponding to small amplitude detected signals and in which the number of stepwise increases exceeds three steps.

8. A detector system for recovering a signal modulated upon a carrier, comprising in combination:

crystal detector means responsive to the modulated carrier and operative to provide a detected signal, said crystal detector means having a square-law region for small amplitude detected signals, a linear region for large amplitude detected signals and a transition region for intermediate amplitude detected signals; a logarithmic gain amplifier responsive to said detected signal and operative to provide an amplified signal, said logarithmic gain amplifier having gain which varies as the logarithm of the amplitude of said detected signal; and

stepped gain amplifier means responsive to said amplified signal and operative to provide an output signal which is the logarithm of the signal modulated upon the carrier, the gain of said stepped gain amplifier being responsive to the amplitude of said amplified signal, said stepped gain amplifier having a constant first gain for an amplified signal which corresponds to a small amplitude detected signal, a second gain which is twice as large as said first gain for an amplified signal which corresponds to a large amplitude detected signal and a gain which stepwise increases with the amplitude of said amplified signal from said first gain to said second gain for an amplified signal which corresponds to an intermediate amplitude signal.

9. A detector system, including a crystal detector having a conventional detection range which includes a square-law, transition and linear detection region, for providing an output signal which is linear over the entire detection range of the crystal detector, said detector system comprising, in addition to said crystal detector:

a logarithmic gain amplifier, having a gain which varies as the logarithm of amplitude of an applied signal, connected to receive the detected signal from the crystal detector and to provide an amplified signal; and a stepped gain amplifier connected to receive said amplified signal, to gain of said stepped gain amplifier being responsive to the amplitude of said amplified signal and increasing stepwise from a minimum gain of "A" to a maximum gain of "2A" with an increase in the amplitude of said amplified signal from a signal corresponding to the square-law detection region to a signal corresponding to the linear detection region of said crystal detector.

10. A detector system in accordance with claim 9 in which the gain of said stepped gain amplifier remains constant at a gain "A" for all amplified signals developed with the square-law detection region and remains constant at a gain "2A" for all amplified signals developed with the linear detection region, and stepwise increases in at least three steps from a gain equal to "A" to a gain equal to "2A" with increase of the amplitude of said amplified signal developed with the transition region.
